UNITED STATES PATENT OFFICE.

LUCY COTTON AMENT AND CLARA HILFIKER, OF NEW YORK, N. Y.

COLLAPSIBLE COMMODE.

Application filed July 22, 1927. Serial No. 207,754.

This invention relates to a commode or chamber which for convenience in carrying as when travelling may be collapsed and contained within a case or other receptacle 5 which will occupy the minimum amount of space.

The principal object of the invention is the provision of such a commode which may be readily and quickly expanded to its full 10 height and size, without providing complicated or cumbersome mechanism which would make its manufacture expensive.

Another important object is the provision in a device of the character described, of 15 suitable supporting means capable of supporting the weight of a person, yet light and strong and which may be folded when not in use.

To this end the invention contemplates 20 top and bottom metallic supporting rims between which is secured a rubber body, preferably in cylindrical form as by means of attaching rings. Suitable folding arms attached to the top and bottom rings support 25 the top rim when the device is unfolded, but which when collapsed will lie within the contour of either top or bottom rim. This allows the device when folded to occupy the minimum amount of space.

30 In some instances it is desirable to provide a container closed at the bottom and attached to the top rim only and hanging free therefrom. In this case the same folding arms would be used to support the device. 35 This last named modification would facilitate the keeping of the device in a sanitary condition.

The invention further consists in the novel arrangement, combination and construction 40 of parts more fully hereinafter described and shown in the drawings.

In the drawings:—

Fig. 1 is a perspective view of a device 45 embodying the invention.

Fig. 2 is a sectional elevation of the device of Fig. 1.

Fig. 3 is a sectional elevation of the device collapsed and in a carrying case.

Fig. 4 is a view of a modified form.

50 Fig. 5 is a view of a detail.

Fig. 6 is a fragmentary view showing an arm folded.

A base plate is indicated at 1 and may be made of any desired material such for in-

stance as aluminum, and a top rim preferably of the same material at 2. Between these two parts is provided a sheet rubber cylindrical body 3, the upper margin of which overlies the rim 2 and is secured between the rim and a ring 4 as by means of 55 screw elements 5. The bottom margin of the rubber body is secured to the bottom plate by means of the lower ring 6 and screws 7.

A plurality of foldable supporting arms 65 are provided, three being shown, which are hinged at one end to ears 9 struck out from ring 6, and to ears 10 on top ring 4. The arms are pivoted intermediate these points 70 as at 11, and a stop 12 provided so that movement of the two parts of each arm may be limited to a position just past dead center.

It is to be noted that the ears to which the foldable arms are attached are formed 75 at an angle, that is the plane of the ears when in finished position is not at right angles to a radius of the device. Fig. 5 illustrates a ring with the ear struck out but before bending. When bent into vertical position, and the arm attached, the arm may 80 be folded downwardly and still remain within the contour of the base, as shown in Fig. 6.

The arms are constructed of sufficiently 85 heavy material so that they will withstand and support the weight of a person.

As a modified device, the rubber body may be in the form of a cup 13 attached to the upper rim only and freely hanging therefrom. The arms in this case function as 90 before.

In both forms, it is preferable to use a 95 flexible, strong rubber fabric of a glazed nature which may be easily and readily cleaned, and which will not crack upon repeated folding and unfolding.

A suitable carrying case having a hinged top and handle is indicated at 14. Due to the fact that the rubber body may be collapsed into a small space, only a slight 100 height is necessary for the case.

What we claim is:

1. A device of the character described comprising a base, an upper rim, foldable supports connecting base and rim, a flexible 105 body secured to and depending from the upper rim, said body having a bottom integral with its sides, a marginal flange on said

body extending outwardly from the body bottom and in the same plane therewith, said flange being secured to said base.

2. A device of the character described, comprising a base, an upper rim, foldable supports connecting base and rim, and a flexible body secured to and depending from the upper rim, said supports when folded

lying outside the collapsed body and inside the contour of the base cutting the base on a 10 segmental line.

In testimony whereof, we affix our signatures.

LUCY COTTON AMENT.
CLARA HILFIKER.
